UNITED STATES PATENT OFFICE.

THOMAS EUBANK, OF LITTLE ROCK, ARKANSAS, ASSIGNOR TO THE
WESTERN RAILWAY EQUIPMENT COMPANY, OF EAST ST. LOUIS,
ILLINOIS.

CAR-ROOF.

SPECIFICATION forming part of Letters Patent No. 591,665, dated October 12, 1897.

Application filed December 30, 1896. Serial No. 617,528. (No model.)

To all whom it may concern:

Be it known that I, THOMAS EUBANK, a citizen of the United States, residing at the city of Little Rock, in the county of Pulaski, State 5 of Arkansas, have invented a certain new and useful Improvement in Car-Roofs, of which the following is a full, clear, and exact description, reference being had to the accompanying drawings, forming a part of this specification, wherein—

Figure 1 is a perspective view of a car-roof embodying my invention. Fig. 2 is a top plan view of a portion of the same. Fig. 3 is a cross-sectional view on line x x , Fig. 2. 15 Fig. 4 is an enlarged sectional view showing the end of one of the truss-rods.

The roof of a car is one of the most important parts in car construction, as its functions are to protect the contents of the car 20 from damage. For some unexplained reason, little thought, until recently, has been given to the causes of failures of car-roofs—as to whether such failure was due to lack of strength in the construction or to the roof-sheathing employed. In most cases the blame 25 was laid on the iron or tin forming the roof-sheets or the manner of joining the sheets together, when, as a matter of fact, the cause of failure was not due to the material employed in the roof-sheathing nor the manner 30 of joining the sheets together, but was due almost entirely to the lack of bracing the roof. Cars as ordinarily constructed have no strength in their roof-supports, because the 35 purlins, carlines, and ridge-pole are not put together to resist the torsional or twisting strain to which a loaded car is subjected in swinging around curves. The roof-supports in ordinary cars yielding under such strain 40 cause the roofing-sheets to buckle and break, rendering the roof useless for the purposes for which it was designed—that is, shedding water and preventing its entrance into the car.

My invention contemplates an improvement 45 in supports for car-roofs, and is comprehended in the lateral braces which I employ and the manner in which I truss the roof-supports. I do not claim that lateral braces in car-roofs are broadly new, for it is a well-known fact

that they were used many years ago, the braces 50 being taut in the carlines, purlins, and ridge-pole flush with the same. The manner in which this construction was put together made it very expensive, the cost prohibiting its use in ordinary cars. I do not claim to be 55 original in the application of carline-rods to tie the upper portions of a box-car together; but I do claim the manner in which I use these carline-rods, making them the truss-rods, and also the manner in which I secure 60 these truss-rods in place to prevent the nuts from coming loose, which would render the rods useless, and I also claim the use of the rods in securing the hood in position.

In the matter of bracing the roof-supports 65 I claim the lateral braces in skeleton form and also the manner of applying strips to the ridge-pole, purlins, and carlines to make said parts flush with the braces.

In the drawings, A indicates the side walls 70 of a car; B, the plate; C, the cornice; D, the hood, and E the roof-sheathing. These parts may be of any ordinary or approved construction.

F indicates the ridge-pole, G the purlins, 75 and H the carlines, which parts may also be of any approved construction.

I indicates lateral braces, which are preferably arranged in skeleton form, as shown in Fig. 1—that is, two diamonds are formed 80 throughout the length of the car-body. The ends of the several pieces forming these diamonds are preferably jointed together in such manner as to make a solid structure. These braces are nailed or otherwise secured to the 85 plate, carlines, purlins, and ridge-pole, upon which they are primarily arranged in constructing the roof-support according to my invention.

b , f , g , and h are strips of a thickness sub- 90 stantially the same as the thickness of the lateral braces I. These strips are arranged, respectively, upon the plate, ridge-pole, purlins, and carlines, their office being to build up the plate, ridge-pole, purlins, and carlines, 95 so that the upper faces of said parts will be flush with the lateral braces. These strips fit snugly against each other and against the

lateral braces, and being fastened by nails or screws to their respective parts make a rigid support for the roof.

J indicates truss-blocks secured to the sides 5 of the carlines beneath the ridge-pole, which truss-blocks are recessed in their lower ends to receive the truss-rods K. The ends of this truss-rod pass through the plates B, side wall A, cornice C, and hood D. Suitable threads 10 are cut on the ends of the rod, and a nut k is turned down against the plate B and into a recess in the side wall A. This enables the tension to be placed upon the truss-rod, and by reason of the nuts fitting into non-circular recesses in the walls A they are prevented 15 from coming out by turning backward. If desired, recesses could be made in the cornice to answer the same purpose. The cornice C is arranged over the nuts and prevents their 20 outward movement. A washer k' is strung on the rod between the cornice and hood D, and the extreme outer ends of the truss-rod hold the hoods D in position, supporting them at different points along the entire length of 25 the car. A nut k'' is placed on the rod outside the hood, and being turned down holds the hood in place.

From the above description it will be noted that even should the nuts which impinge 30 against the outer faces of the hoods D become loosened the nuts which impinge against the plates B will still hold the body of the car rigid and prevent bulging.

I am aware that many minor changes in the 35 construction, arrangement, and combination of the several parts of my improved roof can be made and substituted for those herein shown and described without in the least departing from the nature and principle of the 40 invention.

Having thus described my invention, what I claim, and desire to secure by Letters Patent of the United States, is—

1. In a car-roof, the combination with the roof-timbers, of braces arranged upon said 45 timbers, and strips arranged upon said timbers to build the same up flush with said braces; substantially as described.

2. The combination with the plates, ridge-pole, carlines and purlins, of lateral braces 50 arranged thereon, and strips arranged on the plates, ridge-pole, carlines and purlins, to build said parts up and make their faces flush with the lateral braces, substantially as described.

3. The combination with the plates, ridge-pole, carlines and purlins, of lateral braces arranged thereon in skeleton form, the ends of said braces abutting against each other forming diamond-shaped figures throughout the 60 length of the car, and flushing-strips on the plates, ridge-pole, carlines and purlins, substantially as described.

4. The combination with the truss-rod which passes through the plate, of a nut on 65 said rod which impinges against the outer face of the plate, the side walls of the car formed with a recess which receives said nut, a cornice arranged over the nut, a washer 70 strung on the truss-rod between the cornice and hood, a hood supported by the truss-rod, and a nut on the truss-rod outside of the hood, substantially as described.

In testimony whereof I hereunto affix my signature, in presence of two witnesses, this 75 9th day of December, 1896.

THOS. EUBANK.
